UNITED STATES PATENT OFFICE

EMIL A. REBISCHKE AND WILLIAM J. REBISCHKE, OF LITTLE FALLS, MINNESOTA

GARAGE DOOR OPENING MECHANISM

Application filed March 14, 1930. Serial No. 435,848.

The present invention relates to a mechanism for opening garage doors and has for its prime object to provide a structure whereby an automobile may be run up to the garage doors and engage an apparatus which will release the garage door opening mechanism so that by backing the automobile the doors will swing outwardly and open thereby eliminating the necessity of the driver getting out of the automobile to open the door as is the common practice.

A still further very important object of the invention is to provide a door opening mechanism of the character above mentioned capable of use for doors swinging inwardly or outwardly.

Another very important object of the invention resides in the provision of a mechanism of this nature which is simple in its construction, inexpensive to manufacture and install, thoroughly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a vertical transverse section through a garage showing the inner sides of the doors with our improved mechanism associated therewith,

Figure 2 is a vertical section taken substantially on the line 2—2 of Figure 1,

Figure 3 is a horizontal section taken substantially on the line 3—3 of Figure 2,

Figure 4 is a perspective view of the rocker for moving the bolt,

Figure 5 is a side elevation of the cam lever,

Figure 6 is a fragmentary view of the upper bolt showing the adjustable connection between the sections thereof.

Referring to the drawings in detail it will be seen that the letter A denotes a garage with a pair of doors D hingedly mounted as at 8 to swing outwardly to an open position.

On the inside of the doorway of the garage at the top thereof are brackets 5 with links 6 pivotally connected thereto. Links 7 are pivotally connected with the links 6 and extend inwardly and are pivotally connected with links 8 pivotally engaged with brackets 9 on the doors D.

Springs 10 are anchored on the brackets 5 and to the pivots between the links 7 and 8 and tend to normally swing the doors outwardly to open position.

An upper bolt 11 is formed of a pair of sections adjustably connected together as indicated at 12 so that the length of the bolt may be changed to meet circumstances. This bolt 11 is slideable through brackets 14 on the inside of one door D adjacent the free edge thereof. A lower bolt 15 is slideable on the inner surface of the other door D adjacent the free edge thereof and is mounted in brackets B.

A lever 17 is pivotally mounted intermediate its ends as at 18 on said one door D as the pin and slot connection 19 with the lower end of the bolt 11. An end of the lever 17 is engaged under a lateral extension 20 on the lower bolt 15. A spring 21 normally holds the bolt 11 in a locking position that is upwardly while a spring 22 normally holds the bolt 15 in a locking position that is downwardly.

Obviously by rocking the lever 17 the bolts 11 and 12 may be retracted to unlocked position so that the doors will swing open. One of the doors is provided with a slot 22 adjacent the lever 17.

A bracket 24 on the outside of the door having the slot 22 pivotally supports a lever 25 having a curved cam arm 26 extending through the slot 22 under the lever 17. A spring 27 engages with the lever 25 to hold the bottom end thereof normally swung outwardly. A pivoted ratchet bar 28 is on the door and is urged upwardly by a spring 29 into engagement with the lower end of the lever 25 to hold it in any position to which it may have been swung.

The automobile approaches the doors of the garage and the bumper engages the lever 25 pushing this lever inwardly so as to cause

the cam arm 26 to rock the lever 17 thereby retracting the bolts 11 and 15. The lever 25 is held in the position to which it is forced by the bumper of the car by means of the ratchet bar 28 as will be apparent. The automobile is then backed away from the door and the doors swing open to their normal position.

While we have herein shown and described our invention associated with a garage door swinging outwardly, it is to be understood that we do not wish to limit ourselves to an outwardly swinging door as obviously the invention can be used with hinged doors swinging either inwardly or outwardly.

It is thought that the construction, utility, operation and advantages of this invention will now be quite apparent to those skilled in this art without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described our invention, what we claim as new is:

1. In combination with a door, and devices for fastening the same in a closed condition including a rockable element, a lever, means for pivotally mounting the lever on the door, said lever having an extension projecting through a slot in said door, and normally directly engaging said rockable element, spring means anchored to the door and engaging said lever for normally urging the same in one direction about its pivot, a rack bar pivotally mounted on said door and spring means impinging against said rack bar for retaining said lever in a predetermined position against the action of said first-mentioned spring means.

2. The combination with a door having a slot, of door fastening elements carried by the door, an actuating lever for moving said elements to a door releasing position, means for pivotally mounting said lever on said door, spring means normally urging said lever in one direction for releasing said door fastening element, a rack bar pivotally mounted on said door, and a second spring means urging said rack bar into engagement with one end of said lever for retaining the same in a predetermined position, said lever being capable for engagement with a vehicle whereby the lever may be moved by the vehicle out of engagement with said lever.

3. A vehicle actuated latch control means for the latching elements associated with a garage door, comprising a lever pivotally mounted on the door and having an offset longitudinally curved end portion projecting through a slot in the door for engagement with a movable part of the door latch means, a spring member interposed between the free end of the lever and door for normally spacing said end of the lever relative to the door, a rack bar pivoted at one end to the door, and a spring element anchored to the door and engaging the rack bar for urging the latter into engagement with said free end of the lever for retaining the lever against movement under the expanding action of said first-mentioned spring immediately subsequent to a contraction or expansion of said first-mentioned spring.

In testimony whereof we affix our signatures.

EMIL A. REBISCHKE.
WM. J. REBISCHKE.
